UNITED STATES PATENT OFFICE.

JOHN F. O'CONNOR, OF CHICAGO, ILLINOIS, ASSIGNOR TO WILLIAM H. MINER, OF CHAZY, NEW YORK.

ROCKER SIDE BEARING.

1,290,327.

Specification of Letters Patent.

Patented Jan. 7, 1919.

Application filed April 1, 1918. Serial No. 225,885.

To all whom it may concern:

Be it known that I, JOHN F. O'CONNOR, a citizen of the United States, residing at Chicago, in the county of Cook and State of Illinois, have invented a certain new and useful Improvement in Rocker Side Bearings, of which the following is a full, clear, concise, and exact description, reference being had to the accompanying drawings, 10 forming a part of this specification.

This invention relates to improvements in rocker side bearings.

One object of the invention is to provide a relatively cheap rocker side bearing suitable 15 for railway cars, which side bearing includes a minimum number of parts and so designed that the rocked will automatically return to normal position after each actuation under the influence of gravity.

Another and more specific object of the 20 invention is to provide a rocker side bearing of the type indicated so arranged that the rocker element may be employed in any one of a plurality of positions so as to successively present different sets of wearing surfaces for the purpose of prolonging the life 25 of the device.

In the drawing forming a part of this 30 specification, Figure 1 is a vertical, sectional view through portions of the body and truck bolsters of a railway car showing my improved side bearing in operative relation therewith. The full section lines of the rocker indicate the normal position of the 35 latter and the dotted lines the position of the rocker at the end of its travel in one direction. Fig. 2 is a top plan view of the side bearing proper. And Fig. 3 is a vertical, sectional view, taken substantially on 40 the line 3—3 of Fig. 1.

In said drawing, 10 denotes the under side 45 of a body bolster of a railway car and 11 the upper portion of an opposed truck bolster. In the drawing, the improved side bearing is shown attached to the truck bolster.

The improved side bearing, as shown, includes two elements, a retaining or base casting A and a rocker or anti-friction element B.

The retaining member A is of substantially hollow box-like form having a bottom bearing wall 12, spaced parallel side walls 13—13, and oppositely curved end 55 walls 14—14, the latter being adapted to

serve as limiting stops for the anti-friction element B. At each end, the member A is provided with extended ears 15—15 by which the member is adapted to be riveted to the truck bolster.

The anti-friction element B is shown as in the form of a rocker of polygonal vertical cross section. In general outline, the rocker is more or less triangular and is composed of three sets of opposite, concentric, curved bearing surfaces 16 and 116 of different radii. The surface 116 of each series is of relatively short radius and the corresponding opposite curved concentric surface 16 is of relatively long radius. As will be understood, each short radius surface 116 merges into two bearing surfaces 16 of longer radius and disposed on each side thereof, the whole effecting the general triangular formation above referred to.

With the arrangement of concentric surfaces of different radii in series as above described, it is evident that the rocker in its movement from normal will maintain a fixed vertical distance between the points of contact of the rocker with the opposed surfaces on the two bolsters. Furthermore, with the rocker arranged as shown, it will be seen that it will automatically return to normal under the influence of gravity after each actuation and removal of the pressure.

In order to positively maintain the proper relation between the rocker and its retaining casting, the latter is provided with a series of spherical knobs 17—17 adapted to 90 coöperate with corresponding recesses 18 on all the sides of the rocker. In this manner, the rocker cannot be shifted bodily with respect to the retaining casting A.

In order to reduce the amount of metal 95 in the rocker and also to insure proper and uniform cooling and annealing of the cast metal from which the rocker B is made, the same is preferably provided with a series of transversely extending openings 19—19 100 and 20 symmetrically arranged with regard to the center and surfaces of the rocker.

With the construction shown, it is evident that any one of the series of opposed concentric surfaces 16 and 116 may be 105 brought into action by merely turning the rocker so as to present the desired surface 16 at the bottom and the corresponding surface 116 at the top. In this manner, the rocker may be termed reversible or adjust- 110

able and, as any surfaces become worn, the position of the rocker is changed to present new surfaces for the purpose of prolonging the life of the device.

5 The side walls of the retaining member may be cut away, as indicated at 21—21, to permit all foreign matter to be readily washed out and thereby avoid interference with the free movements of the rocker.

10 I claim:

1. In a side bearing of the character described, the combination with a retaining member having a bearing seat, of a rocker of generally polygonal cross section, said rocker having a plurality of series of opposed concentric curved bearing faces of different radii, one bearing face of each series being adapted to rock on said bearing seat and the opposed bearing face to engage an opposite member, the position of said rocker as an entirety being shiftable with respect to its retaining member so as to thereby utilize any one of the series of opposed bearing faces.

2. In a side bearing of the character described, the combination with a retaining member having a bearing seat, of a rocker of generally polygonal cross section, said rocker having a plurality of series of opposed concentric curved bearing faces of different radii, one bearing face of each series being adapted to rock on said bearing seat and the opposed bearing face to engage an opposite member, the position of said rocker as an entirety being shiftable with respect to its retaining member so as to thereby utilize any one of the series of opposed bearing faces, and coöperating inter-engaging projections and recesses on said rocker and member for positively maintaining the proper relation of the rocker and

member after each actuation of the side bearing.

3. In a side bearing, the combination with a hollow box-like base casting adapted to be secured to a truck bolster, of a rocker of substantially polygonal cross section mounted within said base casting, said rocker having a plurality of series of opposed concentric curved bearing faces of different radii.

4. In a side bearing, the combination with a hollow box-like base casting adapted to be secured to a truck bolster, of a rocker of substantially polygonal cross section mounted within said base casting, said rocker having a plurality of series of opposed concentric curved bearing faces of different radii, said rocker being detachably mounted within the base casting and adapted to have its position as an entirety changed with respect to the base casting so as to utilize actively any one of said series of concentric bearing faces.

5. In a side bearing of the character described, the combination with a retaining member, of a rocker of generally polygonal cross section, said rocker having a plurality of series of concentric curved bearing surfaces of different radii, any one of which series may be utilized actively, said retaining member having a plurality of projections, and all surfaces of said rocker being provided with corresponding recesses co-operable with said projections in any relative arrangement of said rocker and retaining member.

In witness that I claim the foregoing I have hereunto subscribed my name this 27th day of Mar., 1918.

JOHN F. O'CONNOR.
